CLAIM

The ornamental design for a compartmented medical test tray, substantially as shown and described.

DESCRIPTION

FIG. 1 is a front perspective view of a compartmented medical test tray showing my new design;

FIG. 2 is a front elevational view of the test tray of FIG. 1 as viewed in the direction of the arrows labeled 1—1;

FIG. 3 is a right side elevational view of the test tray of FIG. 2; and

FIG. 4 is an elevational view of the rear of the test tray of FIG. 2 as viewed in the direction of the arrows labeled 4—4 in FIG. 3.
